MERCURY SWITCH

Harry L. Lambert, Enfield, N. Y., assignor to Allen Wales Adding Machine Corporation, Ithaca, N. Y.

Application July 27, 1942, Serial No. 452,405

12 Claims. (Cl. 200—80)

This invention relates to electric switches and particularly to the type known as "mercury tube" switches. Switches of this type are useful to control a circuit for any purpose, and to control the speed of a rotating element by controlling the circuit of the driving motor, as for example, in calculating machines where such machines are often placed, by their users on different surfaces which vary from a level condition to quite a substantial extent. It has been found that when such switches as heretofore made, are operated by centrifugal forces developed by rotation of an element, the speed at which the switch will be operated will be different when the machine is in different positions, such as when the machine is resting upon surfaces having different inclinations.

The present application is in the nature of an improvement upon the mercury switches disclosed and claimed in my prior applications, Serial Nos. 296,124 and 420,507, the latter being now Patent No. 2,301,217 of November 10, 1942. The switches of those prior applications filed September 22, 1939, and November 26, 1941, respectively, utilize a globule of mercury which makes or breaks a circuit by changes in the shape of the globule against the action of its surface tension, while the globule rests on a surface which it does not wet and remains undivided and in the same relative position on the surface during its distortion or change of shape.

Mercury tube switches as heretofore made also have been relatively expensive and required special mountings and skilled labor in order to enable replacement of the switches, if they became broken or inactive for any purpose.

An object of this invention is to improve and simplify mercury switches of the type utilizing a globule of mercury as the medium which makes and breaks the circuit, which may be replaced in the same simple manner employed to replace an electric light bulb in a socket included in the circuit to be controlled, which switch will be small and compact, which will be protected against breakage, as much as possible, which may be easily exhausted and its chamber for the mercury filled with an inert gas in a simple manner, and which will be relatively simple, compact, durable and inexpensive.

Another object of the invention is to provide an improved mercury globule type of switch in which the globule, by changes in its shape against the forces of surface tension and while it remains undivided, will change the conducting condition of a circuit in which it is included, at the same

speed irrespective of the position in which the switch is supported when operating, and which will be relatively simple, accurate in the control it provides, compact and inexpensive.

5 Another object of the invention is to provide an improved mercury switch, which, when employed as a governor control for the electric circuit of a motor, will make the circuit when the machine stops and while the device is in any position or inclination, which will open the circuit to be controlled thereby when a selected speed is obtained, irrespective of the inclination of the surface on which such device is supported.

10 Various other objects and advantages will be apparent from the following description of several embodiments of the invention, and the novel features will be particularly pointed out herein-after in connection with the appended claims.

In the accompanying drawing:

15 Fig. 1 is a side elevation of a rotating element, with a portion shown in section, having thereon a circuit controller constructed in accordance with this invention;

20 Fig. 2 is a transverse sectional elevation of the same, the section being taken approximately along the line 2—2 of Fig. 1;

25 Fig. 3 is a longitudinal sectional elevation through a mercury tube switch representing one embodiment of the invention;

30 Fig. 4 is a transverse sectional elevation through the same, the section being taken approximately along the line 4—4 of Fig. 3;

35 Fig. 5 is a longitudinal sectional elevation through a switch, also constructed in accordance with the invention, and similar to the embodiment shown in Figs. 3 and 4, but illustrating a slight modification thereof;

40 Fig. 6 is a similar longitudinal sectional elevation through a mercury tube switch also constructed in accordance with the invention, but illustrating still another embodiment of the invention;

45 Figs. 7 to 10 are diagrams illustrating how the mercury globule closes the circuit through the switch when the switch is in a plurality of different positions, and by the dash lines, how the mercury globule moves into an effective position to control the circuit in which it is included at the same speed, regardless of the inclination to the horizontal in which the axis of the tube is placed; and

50 Figs. 11 and 12 are longitudinal and cross sectional elevations respectively of mercury switches which may also utilize some features of the invention.

Referring first to Figs. 1 to 4, the shaft 1 may be the shaft of a motor, or a shaft driven by a motor through a suitable gear reduction mechanism, or just a rotating shaft. The improved circuit controller is mounted on the shaft 1, and for this purpose, the mounting includes a base element or member 2 of insulating material which has a recess 5 that fits over the shaft and is secured thereon in any suitable manner, such as by a set screw 4. In the outer end face of the member 2 is a recess 5, Fig. 2, which is eccentric to the axis of rotation of the shaft 1, and a base 6 is disposed in the eccentric recess 5. The recess is, of course, circular in shape and the base 6 has a circular periphery so that it may be rotated in the recess 5. Straps 7 are secured to the outer face of member 2 in any suitable manner, such as by screws 8, and overlie the outer face of the base 6 so as to confine the latter within the recess 5 while permitting rotation of the base 6 in the recess 5. By tightening the screws 8, the friction of the straps 7 on the base 6 may be varied, so that after the base 6 has been rotated into any selected position in the recess 5, a tightening of the screws 8 will clamp the base 6 in that adjusted position and cause it to rotate as a unit with the base element 2.

Mounted on the exposed end face of the base 6 is a socket element 9 of any suitable construction, such as of the type employed in automobile lights for removably mounting the electric light bulbs. This socket element 9 is mounted on the base 6 eccentrically of the periphery of that base, as shown in Fig. 2, so that when the base 6 is rotated in the recess 5, the socket element 9 will be shifted into positions having different radial distances from the axis of rotation of the shaft 1.

An improved mercury tube switch A (Figs. 1 and 2) is mounted removably in the socket element 9, and for this purpose, the switch A has a metal sleeve or ferrule 10 on its base, which ferrule is telescopically received in the cavity of the socket element 9 and has a pin 11 projecting radially therefrom so as to be received in a bayonet slot 12 in the side wall of socket element 9. When the switch A is inserted in the socket element 9, the pin 11 is first placed in alignment with the entrance end of the slot 12, the switch element then moved endwise into the socket element 9, and then it is given a turn so as to carry the pin 11 into the offset end of the bayonet slot 12 and lock the switch A releasably in the socket element 9. The opposite face of the member 2 carries collector rings 13 and 14, circular in character and approximately concentric with the shaft 1, and formed of metal or other electricity conducting material. Brushes 15 and 16 are suitably mounted on a support 17 so as to bear upon the collector rings 13 and 14 respectively as the latter rotates with the shaft 1. The brushes are insulated from the support 17, and for this purpose, the latter may be made of insulating material, and the brushes are electrically connected to circuit wires 18 and 19. A wire 20 leads from the collector ring 14 to the side wall or tubular part of the socket element 9 which is of metal, and a wire 21 connects the collector ring 13 to a central yielding contact 22 in the bottom of the socket element as usual in this type of socket, and which contact 22 is engaged by a central terminal or contact on the end of the switch A.

In Figs. 3 and 4, one embodiment of the im-

proved switch tube is illustrated, and this switch in the form here shown, includes a hollow, somewhat spherical, cup-like casing 23 of a metal not wet by mercury, or at least having on its inner face a metal coating not wet by mercury. This casing has an opening at one side or end, with a cylindrical flange 24 around that opening. A wall 25 of glass is applied, while plastic, to the flange 24 so as to receive intended therein the flange 24. The glass forms a seal with the flange 24 and closes the opening. The glass 25 and the metal casing 23 are chosen so as to have approximately the same coefficient of thermal expansion. A common metal not wet by mercury and which is frequently used in the manufacture of mercury switches is iron alone or in alloy form. One form of metal not wet by mercury, and which has a coefficient of thermal expansion approximately that of glass is available in the open market under the trade name of "Kovar," and glass suitable for this purpose which has approximately the same coefficient of thermal expansion as the Kovar metal is available in the open market. The glass wall 25 as applied to the flange 24, has a small, tube-like extension 26, and after the glass wall 25 has been sealed to the flange 24, a globule of mercury may be inserted through this tube 26 into the chamber of the casing 23, the atmosphere of the casing chamber exhausted, and an inert gas inserted into the chamber so as to prevent deterioration of the mercury and contact surfaces within the chamber when making and breaking a circuit. The tube 26 is then fused or drawn so as to close it, as usual in the manufacture of light bulbs and glass mercury tube switches. This fused and drawn tube 26 is shown in Fig. 3 as extending outwardly from the outer face of the glass wall 25.

A conductor 27 which is also of a metal having approximately the same rate of expansion as glass, passes through the glass wall 25 approximately centrally thereof, and the end of this conductor 27 which is within the chamber of the casing 23 terminates in a head 28 whose surface is everywhere equidistant from the inner surface of the casing 23. When the chamber of casing 23 has the curvature of a sphere, the head 28 will be spherical and concentric thereto. The diameter of the head 28 is sufficiently small to enable it to be passed through the opening surrounded by the flange 24, and the element 27 is preferably passed through the glass wall before that glass wall is applied to the flange 24. The conductor 27 is so placed in the glass wall that the head 28 will be approximately concentric with the wall of the casing 23 which defines the chamber.

Within the chamber of the casing 23 is a globule 29 of mercury or of any other electrically conducting liquid having a strong surface tension. Mercury is the conducting liquid most commonly employed for this purpose, because of its exceptionally high surface tension. This globule of mercury is of a size which only partially fills the chamber in the casing 23, and when resting on the wall of the casing 23 will contact the head 28, as shown clearly in Figs. 3 and 4. This globule of mercury thus forms an electrical connection between the casing 23 and the head 28. The mercury globule is also of a size to assume a curved form in which a substantial portion thereof is held away from and against spreading along the chamber wall of casing 23 solely by its surface tension in opposition to gravity,

and such a mass of mercury when resting on a surface which it does not wet usually assumes a somewhat ball-like form which may be distorted or flattened somewhat, depending upon the action of gravity on the mass of the mercury forming the globule, and which flattening obviously becomes greater progressively as the size of the globule increases.

The metal sleeve 10 telescopes over the glass wall 25, abuts against the casing 23, and may be electrically connected to the casing 23 in any suitable manner, such as by a drop 30 of solder or welding material. This tube 10 is in the nature of a metallic sleeve which thus projects away from the casing 23 and past the wall 25, so as to protect the latter and the fused tube tip 26. The conductor 27 extends approximately to the end of the sleeve 10 where it terminates in a contact head or button 31. The outer end of the sleeve 10 is closed by a disk or button 32 of insulating material through which the conductor 27 extends and against the face of which the head 31 abuts. The space within the sleeve 10 between the disk 32 and the glass wall 25 is filled with a suitable insulating material 33, and it may be a filling similar to the fillings commonly employed in electric incandescent lamps, or it may be any insulating pitch or plastic material which is applied, while it is plastic, to the interior of the sleeve 10. If desired, this insulating material may extend past the periphery of the glass wall 25 so as to form a liner for the sleeve 10 and prevent metal to glass contact between the sleeve 10 and the glass wall 25. This sleeve 10 carries the bayonet joint pin 11.

In this embodiment of the invention, the glass wall 25 has an integral projection 34 which surrounds the conductor 27 to the spherical head 28, so that the globule of mercury can only make contact between the casing 23 and the conductor 27 through the head 28 and not by direct contact of the globule of mercury with the conductor rod 27 beyond the head 28. It will be noted that the radial distance from the periphery of the head 28 to the periphery of the chamber in the casing 23 will be substantially equal everywhere around the head 28, and therefore, no matter where the globule of mercury 29 is disposed in the chamber of the casing 23, it will electrically connect the head 28 and the casing 23 and the same degree of flattening of the globule of mercury will be necessary to open the circuit between the casing 23 and the head 28, whether the mercury globule 29 is in one position or another in the casing chamber. Thus when the switch shown in Figs. 3 and 4 is mounted in the socket element 9, as shown in Figs. 1 and 2, the mercury will form an electrical connection between the circuit wires 18 and 19.

It will be noted also that in this form of the invention, the longitudinal axis of the switch which, in the form shown in Figs. 3 and 4 is approximately coincident with the conductor 27, will be disposed parallel to the axis of the shaft 1, but at one side of and parallel thereto. Thus when the shaft 1 rotates, the globule 29 will move into the zone of the surface defining the chamber of casing 23, which is farthest from the axis of rotation, and it will remain in that position undivided and relatively immovable thereon throughout such rotation and in all variations of speed. As the speed of rotation of the switch tube increases, centrifugal forces tend to flatten the globule against the action of its surface tension, and when the speed has

reached some particular speed, the flattening of the mercury globule will be sufficient to break contact between it and the head 28, as shown by dotted lines in Figs. 3-9 and 11, and thus open the circuit between the circuit wires 18 and 19. The circuit wires 18 and 19 may control a signal which indicates by the breaking of the circuit that a particular speed has been reached or exceeded, or the circuit wires 18 and 19 may be in series with the motor driving the shaft 1, so as to act as a governor therefore, or the wires 18 and 19 may be in a relay circuit which controls the circuit for the motor which drives the shaft 1.

When the wires 18 and 19 control the motor, then the mercury tube switch acts as a governor for the speed of the motor and holds the speed to a particular speed. By rotating the base 6 in the recess 5, this switch tube may be shifted toward and from the axis of rotation, so as to determine the speed at which the mercury globule opens the circuit between the wires 18 and 19. The size of the globule of mercury will also have some effect upon the speed of rotation at which the shaft 1 at the circuit through wires 18 and 19 will be broken because, if the globule of mercury 29 is larger, a greater degree of flattening of the globule will be necessary before it will leave contact with the head 28.

The embodiment of the invention shown in Fig. 5 is the same as that shown in Figs. 3 and 4, except that the projection 34 on the glass wall 25 has been omitted, and otherwise corresponding parts are designated by corresponding reference characters.

In Fig. 6 another embodiment of the invention is illustrated, in which the casing 35 is made of glass similar to that of the glass wall 25 in Figs. 3 to 5, and this glass casing 35 is provided with a generally spherical chamber 36. The casing 35 has a relatively thicker wall 37 at one side with a capillary tube 38 similar to the part 26 in Figs. 3 and 4, through which mercury may be inserted and the chamber 36 in the casing exhausted of air and refilled with an inert gas. The capillary tube is then sealed in the manner that electric light bulbs and glass tube mercury switches are sealed. A conductor rod 27, similar to the rod 27 of Figs. 3 to 5, extends through the wall 37 and into the chamber 36 of the casing 35 and there terminates in a spherical head 28. The rod 27 and head 28 are, of course, made of metal not wet by mercury, preferably one such as Kovar hereinabove referred to and which has approximately the same coefficient of thermal expansion as that of which the glass of the casing 35 and wall 37 is made. Received over a shoulder on the wall 37 is the metal sleeve 10 corresponding to the sleeve 10 of Figs. 1 to 5.

A conductor 39 also extends through the wall 37 in spaced relation to the rod 27 and the portion of that conductor within the chamber of the casing 35 is threaded somewhat spirally across the chamber 36 in contact with the inner peripheral wall of the casing, and with the turns 40 thereof spaced somewhat from one another, as shown in Fig. 6. The outer end of the conductor 39 extends along within the sleeve 10 and is electrically and mechanically connected to the free end edge of the sleeve 10, such as by welding, soldering or in any other manner. The interior of the sleeve, in this embodiment of the invention, is also filled with a suitable filler 41, similar to the filler 33 of Figs. 1 to 5. A globule 29 of mercury is also placed in the chamber 36 so as

to normally contact the spherical head 28. The turns 40 of the conductor 39 are sufficiently close together so that the mercury globule will always contact with at least one of the turns 40 in every position around the interior of the casing 35, into which the globule may move as the casing is tilted into different positions.

Since the turns 40 of the conductor are spaced from the spherical head 28, the globule will normally connect the conductor 39 to the head 28 in all positions in which the casing 35 may be placed, but if the casing is rotated, such as about an axis generally parallel to but offset from the axis of the rod 27 or the axis of the sleeve 10, the globule of mercury will move into a position on the portion of the inner wall of the casing 35, which is farthest from the axis of rotation, and when flattened by centrifugal forces, will leave contact with the head 28, and thus open the circuit between the head 28 and conductor 39. The portion of conductor 39 which passes through wall 37 is also preferably made of Kovar metal or similar metal, and the portion within the chamber is either of the same material or some material, such as iron, which is not wet by mercury.

In Figs. 7 to 9, I have illustrated diagrammatically the position of the globule of mercury in the casing 23, when the casing is supported in different inclined positions. For example, in Fig. 7, the switch is supported in an upright position in which the rod 27 extends vertically, and the globule 29 of mercury settles to the bottom, as shown by full lines in Fig. 7, where it electrically connects the head 28 and the casing 23. If this switch, shown in Fig. 7, is rotated about an axis parallel to but offset from the rod 27, such as about a vertical axis to the right of the casing 23 in Fig. 7, the mercury globule 29 will move into the position shown by dash lines in Fig. 7, where it still connects the casing 23 and the sleeve 10, until the centrifugal forces become great enough to flatten the globule and cause it to open the circuit. It will be noted, however, that the globule 29 normally closes the circuit between the conductor rod 27 and the casing 23, even though the switch extends upwardly.

In Fig. 8 a switch disposed at an acute angle to the horizontal is shown, that is, tipped sideways from the position shown in Fig. 7, and the mercury globule 29 still connects the casing 23 to the head 28, but if the switch is rotated about an axis parallel to but at one side of the conductor rod 27, the globule of mercury will move into a relative position that is approximately the same as shown in Fig. 7, by the dash line, but if the switch is rotated about an axis, such as shown by the dot and dash line B-B in Fig. 8, then the globule of mercury will move into the dash line position shown in Fig. 8, and will function to open and close the circuit in the manner explained in connection with Fig. 7.

In Fig. 9, the same switch is disposed so as to depend from its support, and the globule of mercury will settle to the end which is then lowermost, as shown by full lines in Fig. 9 and connect the casing and head, and if the tube is then rotated about an axis parallel to but at the right of the rod 27 in Fig. 9, the mercury globule will move into the position shown by dash lines in Fig. 9, and function as explained in Figs. 1 to 8.

In Fig. 10, a switch of the type shown in Fig. 6 is tilted into a position similar to that shown for Fig. 8, so as to illustrate how the globule 29 of mercury functions in the same man-

ner as explained for Figs. 1 to 9, irrespective of the inclination or position of the switch.

It will be noted that the circuit between the wires 20 and 21 will be closed in any position of the switch and in any inclination, and as soon as the operation starts, the mercury globule will move while still connecting wires 20 and 21 into its expected position on the casing wall portion which is then farthest from the axis of rotation.

In Figs. 11 and 12, certain features of this invention are shown as having been incorporated in still another embodiment. In this form, the casing 23a, instead of being generally spherical, as in Figs. 1 to 5, is made cylindrical and of Kovar metal or other electrically conducting material not wet by mercury. Both ends of this sleeve are then closed by glass plates 25a and 25b, which are similar to the plate 25 of Figs. 1 to 5. The conductor rod 27 which corresponds to the conductor rod 27 of Figs. 1 to 5, after extending through one end wall 25b, continues across the chamber of the casing of the sleeve 23a and is slidingly received in a recess in the inner face of the end wall 25a. This provides a closed casing with the glass end walls, and this glass of the same material as glass wall 25, has approximately the same coefficient of thermal expansion as the metal, so that a tight seal is obtained. The globule 29 of mercury is also inserted in the chamber of this sleeve 23a so as to contact with the periphery of the conductor rods 27.

The ferrule 10 fits over the end wall 25b as in the other forms of the invention, and the connector rod 27 extends to the end of the sleeve and terminates in the head 31, the same as in Figs. 1 to 6. The mercury and inert gas may be inserted through a capillary tube extension in the end wall 25b, the same as explained for the wall 25 of Figs. 1 to 5, and the sleeve 10 may be connected to the sleeve 23a forming the casing by a small drop of solder or welding material 30a. It will be noted that in this form of the invention, the conductor rod 27 is also everywhere equidistant from the sleeve 23a and the switch is also a unit which can be handled like an electric light bulb to connect or disconnect it from a circuit. It also has the advantage of a metal casing as one of the contacts, yet the casing 23 is a simple sleeve which is relatively easy to make.

The rod 27 may, if desired, be made in a plurality of sections welded together end to end, with the section which passes through the glass wall 25b made of Kovar metal or metal having approximately the same thermal rate of expansion as the glass of wall 25b. The section within the chamber of casing 23a and slidingly received in a recess in the end wall 25a may be made of iron or other metal not wet by mercury.

When any switch of the type shown in Figs. 1 to 6 is disposed in an inclined position, the globule of mercury will close the switch, regardless of the inclination, and as soon as the rotation of the switch occurs, which is usually about an axis that is parallel to and offset from the longitudinal axis of the switch, the mercury will move into a position along the wall which is farthest from the axis of rotation, but this zone may be slightly different, depending upon the original inclination of the axis of the switch, since gravity has a small influence in determining the position on the casing wall which the mercury globule will take when the switch is ro-

tated. Since the head 28 is everywhere equidistant from the chamber wall along which the mercury can move, it follows that the extent of flattening or distortion, which the globule of mercury must undergo to open the circuit will be the same regardless of the position in the casing of the globule at that time.

After a switch of the type shown in Figs. 1 to 6 is set, such as at the factory, to open the circuit at a given speed, no further adjustment of the device will be necessary when the position of the support of the device is changed, because the speed that will cause the circuit to be opened will be the same in all positions of the switch, and the switch will close the circuit when idle in all angular positions in which it may be supported. It will be noted that the glass walls which close the metal casing are protected by metal, yet they give the same advantages as a glass casing in the manufacture of a switch.

It will be understood that various changes in the details, materials, and arrangements of parts, which have been herein described and illustrated in order to explain the nature of the invention, may be made by those skilled in the art within the principle and scope of the invention as expressed in the appended claims.

I claim as my invention:

1. A mercury tube switch comprising a housing having therein a chamber, an electricity conducting element extending into said chamber and terminating within the chamber in an exposed contact member spaced substantially everywhere approximately equidistant from the enclosing wall of said chamber, said housing having an exposed electrically conducting medium progressing along the major part of said enclosing wall, external circuit terminals leading to said medium and to said member, and a globule of mercury within and only partially filling the space in said chamber between said enclosing wall and said member, said globule being of a size to assume a curved form in which a substantial portion thereof is held away from and against spreading along said enclosing wall, solely by its surface tension opposing the action of gravity thereon, and to touch said member and electrically connect it to said medium while resting on said enclosing wall, but separable from said member to electrically disconnect said member and said medium when said globule is distorted, through centrifugal forces acting thereon, by flattening against said enclosing wall against the action of its surface tension, while remaining undivided and in substantially the same relative position on said enclosing wall.

2. A mercury tube switch comprising a housing having therein an approximately spherical chamber, an electricity conducting element extending into said chamber and having within the chamber an exposed contact member of generally spherical form spaced substantially everywhere approximately equidistant from the enclosing wall of said chamber, said housing having an exposed electricity conducting medium progressing along the major part of said enclosing wall, and a globule of mercury within and only partially filling the space in said chamber between said enclosing wall and said member, said globule being of a size to assume a curved form in which a substantial portion thereof is held away from and against spreading along said enclosing wall, solely by its surface tension opposing the action of gravity thereon, and to touch said member and electrically connect it to said

medium while resting on said enclosing wall, but separable from said member to electrically disconnect said member and said medium when said globule is distorted, through centrifugal forces acting thereon, by flattening against said enclosing wall against the action of its surface tension, while remaining undivided and in substantially the same relative position on said enclosing wall.

3. A mercury tube switch comprising a hollow body having an approximately spherical chamber and an exposed electrically conducting medium progressing along the surface of said chamber, an approximately sphere-like element also of electrically conducting material substantially smaller in diameter than the diameter of said chamber disposed approximately centrally of said chamber and having its peripheral spherical surface exposed in said chamber, said medium and said element having electrically conducting terminal extensions on the exterior of said chamber, and a globule of mercury within and only partially filling the space in said chamber between said element and the wall of said chamber, of a size which will assume a somewhat ball-like form by its surface tension acting against the force of gravity, and bridge the radial space between said element and said wall of said chamber and electrically connect said medium and said element, whereby when said body is rotated about an axis eccentric thereto, said globule will remain relatively motionless against a zone of said chamber wall but move therewith and by centrifugal forces undergo a change in its globular shape against the force of surface tension thereof, and by such change in shape to a selected extent, depending upon the centrifugal force acting on the globule, interrupt the circuit through the globule between said medium and said element.

4. A mercury tube switch comprising a hollow casing of a metal not wet by mercury, said casing having an opening in its wall leading to the chamber therein, a wall of glass of approximately the same coefficient of thermal expansion as said metal, engaging and sealed to said casing entirely around said opening, an electrical conductor extending through said glass wall into said chamber and within said chamber terminating in an exposed contact member spaced everywhere approximately equally from the enclosing wall of said casing, electrical leads to said casing and to the external end of said conductor, and a globule of mercury within and only partially filling the space in said chamber between said member and casing and of a size to assume a curved form in which a substantial portion thereof is held solely by its surface tension opposing gravity, away from and against spreading along the chamber wall of said casing and normally touching said member while resting on the chamber wall of said casing, but separable from said member to electrically disconnect said member and casing when said globule is distorted by flattening against said casing and against its surface tension while remaining undivided and in substantially the same relative position on said wall.

5. A mercury tube switch comprising a hollow casing of a metal not wet by mercury, said casing having an opening in its wall leading to the chamber therein, a wall of glass of approximately the same coefficient of thermal expansion as said metal, engaging and sealed to said casing entirely around said opening, an electrical conductor extending through said glass wall into said chamber and within said chamber terminating in an ex-

posed contact member spaced everywhere approximately equally from the enclosing wall of said casing, electrical leads to said casing and to the external end of said conductor, a globule of mercury within and only partially filling the space in said chamber between said member and casing and of a size to assume a curved form in which a substantial portion thereof is held solely by its surface tension opposing gravity, away from and against spreading along the chamber wall of said casing and normally touching said member while resting on the chamber wall of said casing, but separable from said member to electrically disconnect said member and casing when said globule is distorted by flattening against said casing and against its surface tension through centrifugal forces acting thereon, while remaining undivided and in substantially the same relative position on said wall, a metal ferrule surrounding said glass wall, electrically and physically connected to said casing, and a plastic medium filling said ferrule at the outer face of said glass and through which said electrical conductor extends and forms a terminal.

6. A mercury switch comprising a hollow, spherically cup-like casing of a metal not wet by mercury, with the wall of said casing flanged outwardly in a cylindrical manner at the mouth of the cup, a wall of glass of approximately the same coefficient of thermal expansion as said metal, closing the mouth of said casing and having sealed therein the flanged wall of said casing, a conductor extending through said glass into the chamber of said casing and within said chamber terminating in a spherical head smaller than said chamber but spaced everywhere about equidistant from said casing, a globule of mercury within and only partially filling the space within said chamber and of a size to assume a curved form in which a substantial portion thereof is held solely by its surface tension opposing gravity away from and against spreading along the chamber wall and normally touching said head while resting on any part of the chamber wall defined by said casing, but separable from said head to electrically disconnect said head and casing when said globule is distorted by flattening of the same against said casing in opposition to the action of its surface tension through centrifugal forces acting thereon, while the globule remains undivided and in substantially the same relative position on the casing wall exposed in said chamber.

7. A mercury switch comprising a hollow housing of insulating material, an electricity conductor extending through said housing into the chamber thereof and progressing somewhat spirally along the wall defining the chamber to the opposite side of the chamber, a contact member also extending through the housing into said chamber spaced relatively to the said conductor and terminating within said chamber in a head having its exterior surface spaced approximately everywhere equidistant from the wall defining said chamber, and a globule of mercury within and only partially filling the space in said chamber between the said wall and said head, and of a size to assume a curved form in which a substantial portion thereof is held away from and against spreading along the chamber wall solely by its surface tension in opposition to the action of gravity thereon, and to touch said head while resting on said chamber wall and in contact with one of said spiral turns of said conductor, but separable from said head when distorted by flattening against said chamber wall in opposition to its surface tension through centrifugal forces acting thereon, while it remains undivided and in substantially the same relative position on said chamber wall.

5 8. A mercury switch comprising a hollow casing of a metal not wet by mercury and which has a coefficient of thermal expansion that is approximately equal to that of a glass, closure means for said casing and formed of said glass applied in sealing relation to an opening of said casing to close the chamber of said casing, a contact member extending through said glass closure means into said chamber and within the chamber exposed for contact, a globule of mercury within and only partially filling said chamber and of a size to assume a curved form in which a substantial portion thereof is held solely by its surface tension opposing gravity away from and against spreading along the chamber wall, and normally touching said contact member while resting on said casing wall but separable from said contact member within said chamber to electrically disconnect said head and casing when it is distorted by flattening against said casing in opposition to the surface tension of the globule through centrifugal forces acting thereon, while the globule remains undivided and in substantially the same relative position on the casing wall, and conducting means extending from said casing in insulated relation to said contact member.

25 9. A mercury switch comprising a hollow casing of a metal not wet by mercury and which has a coefficient of thermal expansion that is approximately equal to that of a glass and a generally spherical chamber, closure means for said casing and formed of said glass applied in sealing relation to an opening of said casing to close the chamber of said casing, a contact member extending through said glass closure means into said chamber and within the chamber having a ball-like head exposed for contact, a globule of mercury within and only partially filling said chamber and of a size to assume a curved form in which a substantial portion thereof is held solely by its surface tension away from and against spreading along the chamber wall, and normally touching said contact member while resting on any part of said casing wall but separable from said contact member within said chamber to electrically disconnect said head and casing when it is distorted by flattening against said casing in opposition to the surface tension of the globule through centrifugal forces acting thereon, while the globule remains undivided and relatively immovable on the casing wall, and circuit connections to said casing and contact member.

30 10. A mercury switch comprising a closed, hollow, generally spherical casing of a material not wet by mercury, and containing an inert atmosphere, a conductor extending into the chamber of said casing and within said chamber terminating in a generally spherical head smaller than said chamber but spaced everywhere from said casing, a globule of mercury within and only partially filling the space within said chamber and of a size to assume a curved form in which a substantial portion thereof is held solely by its surface tension away from and against spreading along the chamber wall and normally touching said head while resting on any part of the chamber wall, but separable from said head to electrically disconnect it from said head and casing when said globule is 35 distorted by flattening of the same again said

casing in opposition to the action of its surface tension through centrifugal forces acting thereon, while the globule remains undivided and relatively immovable on the casing wall exposed in said chamber, and means for including said mercury and conductor in series in part of an electric circuit.

11. A mercury tube switch comprising a hollow casing of a metal not wet by mercury, said casing having an opening in its wall leading to the chamber therein, a wall of glass of approximately the same coefficient of thermal expansion as said metal, engaging and sealed to said casing entirely around said opening, an electrical conductor extending through said glass wall into said chamber and within said chamber terminating in an exposed contact member spaced everywhere approximately equally from the enclosing wall of said casing, electrical leads to said casing and to the external end of said conductor, and a globule of mercury within and only partially filling the space in said chamber between said member and casing and of a size to assume a curved form in which a substantial portion thereof is held solely by its surface tension opposing gravity, away from and against spreading along the chamber wall of said casing and normally touching said member while resting on the chamber wall of said casing, but separable from said member to electrically disconnect said member and casing when said globule is distorted by flattening against said casing and against its surface tension through cen-

trifugal forces acting thereon, while remaining undivided and in substantially the same relative position on said wall.

12. A mercury tube switch comprising a housing having therein a closed switch chamber, an electricity conducting element extending into said chamber and having within the chamber an exposed contact member of generally similar form spaced substantially everywhere approximately equidistant from the enclosing wall of said chamber, said housing having an exposed electricity conductor progressing in turns over the inner face of the major part of said enclosing wall, and a globule of mercury within and only partially filling the space in said chamber between said enclosing wall and said member, said globule being of a size to assume a curved form in which a substantial portion thereof is held away from and against spreading along said enclosing wall, solely by its surface tension opposing the action of gravity thereon, and to touch said member and electrically connect it to said conductor while resting on said enclosing wall, but separable from said member to electrically disconnect said member and said conductor when said globule is distorted, through centrifugal forces acting thereon, by flattening against said enclosing wall against the action of its surface tension, while remaining undivided and in substantially the same relative position on said enclosing wall.

HARRY L. LAMBERT.
